UNITED STATES PATENT OFFICE.

HERMAN A. KELLER, OF CHICAGO, ILLINOIS, ASSIGNOR TO KABO CORSET COMPANY, OF CHICAGO, ILLINOIS, A CORPORATION OF WEST VIRGINIA.

STUD MEMBER FOR GARTER-CLASPS.

Specification of Letters Patent. Patented Dec. 10, 1918.

1,287,588.

Application filed May 14, 1918. Serial No. 234,510.

To all whom it may concern:

Be it known that I, HERMAN A. KELLER, a citizen of the United States, residing at Chicago, in the county of Cook and State 5 of Illinois, have invented certain new and useful Improvements in Stud Members for Garter-Clasps, of which the following is a specification.

The present invention relates to the construction of a stud base and stud forming a portion of clasps used for garters, which 10 clasps are employed in connecting and disconnecting the garters from the wearer.

The objects of the invention are, to provide 15 a device of the character specified which will be formed entirely from one piece of metal, which will be inexpensive and strong of construction, and which will present throughout smooth, regular surfaces, eliminating sharp 20 or rough edges that would act to tear the garter pad.

A further object of the invention is to so construct the device as to make the portion 25 thereof from which the stud is formed of thinner metal than the base, whereby the upper end of the stud portion may be upset in a manner to form a relatively broad, right-angled shoulder for engagement with the loop of the clasp, said shoulder forming 30 an efficient abutment for the loop portion of the clasp, whereby accidental disengagement between the stud and loop portion is less likely to occur.

The invention further consists in the features of construction and combination of 35 parts hereinafter described and claimed.

In the drawings:

Figure 1 is an elevation showing a portion 40 of a garter with the attachment of the present invention applied thereto;

Fig. 2 is an enlarged plan view of the attachment;

Fig. 3 is an enlarged cross section of the attachment, showing the construction prior 45 to the upsetting of the end of the stud to form the head; and

Fig. 4 is a view similar to Fig. 3, showing the construction when the end of the stud has been upset to form the head.

50 As stated, the device of the present invention is particularly adaptable for use in connection with garter clasps; and, as illustrated in the drawing, it is applied to a garter pad 5, which may be of any suitable

construction. This garter pad has attached 55 thereto a rubber or other tape 6, to the free end of which is connected a loop member 7, forming a portion of the clasp. There is also connected to the pad 5 a tape 8, to the lower end of which are connected the garter 60 supporters (not shown). The foregoing are all well known features of these devices.

The present invention is concerned with the construction of that portion of the clasp embodying the stud and the base plate which 65 carries the stud. The stud base and stud are formed from a single piece of thin sheet-metal 9. As will be seen from Fig. 2, the base portion is of substantially triangular formation, and one side 10 thereof is formed 70 with an elongated slot 11, and a stitching 12 is applied thereto to connect the attachment to the garter pad.

Formed integrally with the base portion 13 is an upwardly extending hollow stud 14, 75 the same being drawn from the metal comprising the base. The drawing operation necessarily reduces the thickness of the walls of this stud, and it is therefore formed of quite thin metal. The stud is closed at its 80 upper end 15 and open at its lower end 16. After it has been formed as in Fig. 3, the upper end of the stud is upset to provide a head 17. Owing to the thinness of the metal, this head can be formed to provide 85 an abrupt right-angled shoulder 18, which effectively engages with the loop portion 7, thereby forming a strong and efficient connection.

As heretofore made, so far as I am aware, 90 the studs have consisted of a separate piece from the base plate, and have been inserted through a hole in said plate and upset on the under side thereof to secure them to the plate. This is an operation requiring considerable time when the devices are produced in quantity, and, moreover, the upset head on the under side of the plate is frequently of a rough character, so that it tears and wears out the garter pad. Also, these studs 95 of the prior art are of solid construction, so far as I am aware, and the shoulders are more or less rounding in character, owing to the solid metal preventing the forming of a head which would present an abrupt 100 right-angled shoulder.

As will be clearly understood, the surfaces of the entire device are smooth and

regular in character and present no roughened edges which would tend to tear the garter pad.

I claim:

5 A garter clasp attachment of the character specified, composed of a single piece of sheet metal and comprising a base plate arranged along one edge for attachment to a garter pad, an upwardly extending hollow

10 stud formed integrally with said base plate,

the walls of said stud being thinner than the metal of the base plate, the upper end of the stud being closed and the lower end open, the thin walls of said stud permitting the said upper end of said stud to be upset 15 and form a head thereon with an abrupt substantially right-angled shoulder at the juncture of the head and body of the stud, substantially as described.

HERMAN A. KELLER.
